UNITED STATES PATENT OFFICE

93,401

DESIGN FOR AN AIR CONDITIONER

Richard C. Jepertinger, Milwaukee, Wis., assignor
to Syncromatic Air Conditioning Corporation,
Milwaukee, Wis., a corporation of Wisconsin

Application July 5, 1934, Serial No. 52,459

Term of patent 14 years

To all whom it may concern:

Be it known that I, RICHARD C. JEPERTINGER, a citizen of the United States, residing at Milwaukee, in the county of Milwaukee and State of Wisconsin, have invented a new, original, and ornamental Design for an Air Conditioner, of which the following is a specification, reference being had to the accompanying drawing, forming part thereof.

The single figure is a perspective view of the air conditioner showing my design.

I claim:

The ornamental design for an air conditioner, as shown.

RICHARD C. JEPERTINGER.
